(57) **CLAIM**

The ornamental design for an edge-lit blade luminaire, as shown and described.

DESCRIPTION

This application also is related to U.S. patent application Ser. No. 29/481,306, filed Feb. 4, 2014 and titled “Edgelit Blade Luminaire,” which is a continuation application of U.S. patent application Ser. No. 29/452,824, filed Apr. 22, 2013, titled “Edgelit Blade Luminaire”.

FIG. 1 is a top perspective view of an edge-lit blade luminaire, showing our new design;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front side elevation view thereof; and,

FIG. 8 is a rear side elevation view thereof.

The broken lines in the drawings illustrate portions of the edge-lit blade luminaire which form no part of the claimed design.
